UNITED STATES PATENT OFFICE.

GUISSEPPE GIDINO, OF TEDDINGTON, ENGLAND.

BURNING OF LIQUID FUEL IN BOILER AND OTHER FURNACES OR HEATING APPARATUS.

Application filed July 6, 1922, Serial No. 573,213, and in Great Britain July 21, 1921.

For burning liquid fuel in steam boiler and other furnaces or heating apparatus, it has heretofore been usual to force the liquid fuel continuously into a combustion chamber to which air is also continuously admitted, as by forced draught, or by the inducing action of the issuing liquid fuel, the supply of liquid fuel and air being controlled by hand operated valves at the discretion of the stoker or attendant. In such modes of producing a combustible mixture of liquid fuel and air it is difficult, if not impossible, to admit only the exact amount of air necessary to effect complete combustion of the liquid fuel, the air being either deficient in quantity or in excess. A further difficulty in effecting the complete combustion of liquid fuel under the conditions mentioned, arise from the fact that different kinds of liquid fuel, both crude and more or less refined, require different amounts of air to effect their complete combustion, whilst variation in atmospheric conditions also produce a variation in the efficiency of the air supplied. As a result, liquid fuel is either wasted, or the temperature of combustion is not so high as it would be if only the exact amount of air necessary for complete combustion of the fuel were used.

Now the present invention has for its object to enable liquid fuel and air to be mixed in the exact proportions necessary for the complete combustion of the liquid fuel whatever may be its nature, the exact proportions when once fixed for the particular kind of liquid fuel to be used, being maintained constant without further attention on the part of a stoker or other person so as thereafter to eliminate the personal element in the control.

For this purpose, the liquid fuel and air are admitted successively by mechanically operated controlling means, in the exact relative proportions necessary to effect the complete combustion of the liquid fuel, to a mixing chamber wherein they are intimately mixed and from which the resulting combustible mixture is delivered into the combustion chamber of a steam generator or other furnace or place wherein combustion of the mixture is to take place for steam generating or other purpose.

The liquid fuel and air are admitted to the mixing chamber successively, in the required proportions, through separate ports

that are opened and closed alternately by mechanical means, the liquid fuel and air being capable of separate control to suit requirement. Usually, the liquid fuel inlet will be opened and closed before the air inlet is opened and closed. In this case, when the liquid fuel is a crude or heavy oil, distributing means may be provided within the mixing chamber for causing it to assume a sub-divided or film form so that when the air, which is delivered under a suitable pressure, enters the mixture chamber, it can readily atomize the liquid fuel and become intimately mixed therewith. To aid in effecting intimate mixture of the air and liquid fuel, the mixing chamber may advantageously be of elongated oval shape in longitudinal section and the air be caused so to enter the said chamber at one end thereof that it will impinge at an angle against the inner surface of the chamber and ricochet in the chamber, the intimate mixture of liquid fuel and air thus produced being delivered through an outlet or nozzle at the opposite end of the chamber. The liquid fluid may enter the chamber by gravity, whilst the air may be delivered into the chamber, under constant pressure, from a pump, or from a compressed air storage chamber, the size of the liquid fuel inlet and its duration of opening, and the size of the air inlet, its duration of opening and the pressure of the air, being such that the amount of liquid fuel and air admitted to the mixing chamber at each operation of the liquid fuel and air mixing apparatus will be such as to attain the hereinbefore described object of the invention. Or the liquid fuel may be sprayed into the mixing chamber under pressure by a suitable atomizing nozzle and then cut off, after which the air is forced into the chamber and the mixture of liquid fuel and air delivered through the chamber outlet or nozzle.

In each case, the production of an intimate mixture of liquid fuel and air is effected in a constantly recurring manner at a rate dependent upon the rate at which the mechanically operated controlling means are worked. The mixture on entering the combustion chamber of a furnace is ignited automatically by any suitable means, as for instance by a constantly burning jet of gas or liquid fuel at the outlet or nozzle end of the mixing chamber, or by an igniting device of known

kind comprising spongy platinum. If the charges of combustible mixture be projected into a combustion chamber containing burning coal, as may be the case, the combustible charges will be ignited thereby.

In order that a continuous jet of combustible mixture may be projected into the combustion chamber and a continuous flame be thereby produced by its combustion, a number of mixing chambers each with its liquid fuel and compressed air inlets and mechanically operated controlling means, may be grouped together and the production of the combustible mixture in the several mixing chambers be so timed as to take place successively in such manner that the discharge of combustible mixture from each chamber will take place before or at the termination of the discharge of combustible mixture from a preceding mixing chamber. In such an arrangement the several mixing chambers may conveniently be grouped around a centre common to them. Each of the mixing chambers may be provided with its own delivery nozzle, or the outlets from the several mixing chambers may have a delivery nozzle common to them.

The mixing chamber, or each mixing chamber when several are used, may consist of an elongated hollow body mounted to oscillate within a stationary casing and be formed with separate liquid fuel and air inlet ports arranged to oscillate past liquid fuel and air inlet ports formed in the stationary casing and with which liquid fuel and compressed air supply pipes communicate, the oscillating hollow body thus forming a combined liquid fuel and air control valve. The oscillating hollow body may be constantly operated in any convenient way. Or the mixing chamber may be stationary and the admission of liquid fuel and air thereto be controlled by separate mechanically operated valves. The liquid fuel and air supply pipes are each provided with a control valve whereby the amount of liquid fuel and air delivered to the mixing chamber at each oscillation thereof can be varied to suit the different qualities of liquid fuel used from time to time. Separate cut off valves may be used to stop the supply of liquid fuel and air when the apparatus is to be put out of use.

The liquid fuel when it is of a crude and heavy nature should be heated to a suitable temperature to render it sufficiently liquid before passing into the mixing chamber. The air should also be heated. Satisfactory results have been attained when the liquid fuel and air have each been heated to a temperature of about 220 to 240° F. As the air is heated and supplied in a practically dry condition under constant pressure, the quantity thereof required for effecting the complete combustion of any particular quality

of liquid fuel after being once determined, will not need to be varied by the stoker or other person by reason of change in external climatic conditions but only, it may be, when liquid fuel of a different quality is to be used.

In some cases, the mixing chamber, may be of such a capacity that it can be used to supply several burners or nozzles with an intimate and regulated mixture of liquid fuel and air. In this case the mixing chamber may be connected through valve controlled pipes to discharge nozzles or burners arranged at a distance from the mixing chamber and to deliver the mixture of liquid fuel and air into one or more furnaces.

Apparatus adapted to produce an intimate mixture of liquid fuel and air in predetermined proportions, as and for the purpose hereinbefore set forth, can be constructed in various forms.

In the accompanying illustrative drawings, Fig. 1 shows in longitudinal vertical section and Fig. 2 in end elevation, one construction of such apparatus comprising a single mixing chamber. Figs. 3 and 4 are cross sections on the line 3-3 and 4-4 respectively of Fig. 1. Fig. 5 shows in longitudinal section part of a modified construction. Fig. 6 shows partly in longitudinal section and partly in side elevation and Fig. 7 in end elevation, a further modified construction of apparatus wherein a number of mixing chambers of the kind shown in Fig. 1 are grouped together for the purpose hereinbefore explained.

Referring to Figs. 1 to 4 inclusive, *a* is a mixing chamber of elongated oval shape in longitudinal section formed in an externally cylindrical body *b* mounted to oscillate in a stationary casing *c*. The body *b* is formed with an outlet port *d* arranged to oscillate past a larger circular inlet port *e* formed in the casing *c* in line with a passage *f* in a branch *g* to which is secured the outlet end of a liquid fuel supply pipe *h* provided with a control valve *i* and a stop valve *i*¹. The body *b* is also formed with an inlet port *m* arranged to oscillate past a port *n* formed in the casing *c* in line with a hole *o* in a branch *p* to which is connected a compressed air supply pipe *r* provided with a control valve *s* and a stop valve *s*¹. The port *m* communicates with a passage *t* that is inclined towards the bottom of the mixing chamber *a* so that the entering air will be directed at an angle to and against the bottom of the chambers for the purpose hereinbefore stated. The passage *t* may however be arranged to direct the entering air at an angle against any other part of the inner surface of the mixture chamber if desired. The body *b* is held in position longitudinally between a mixture outlet nozzle *u* and a cap *v* screwed into opposite ends

of the casing *c* as shown, and is provided with a spindle *w* that extends through a stuffing box *x* in the cap *v*. To the outlet nozzle *u* is secured a delivery nozzle *u'*.

5 The outer end of the spindle *w* is provided with a lever arm 1 provided with a roller 2 that is held, as by a spring 3, against a cam 4, carried by a spindle 5 and rotated by gearing 6 for the purpose of oscillating the body *b*. Packing 7 may be arranged between the oscillating body *b* and the casing *c* to prevent any possibility of liquid fuel leaking from the liquid inlet port *e* to the air port *n*, or of compressed air leaking 15 from the latter port to the liquid fuel inlet port *e*. The packing may be in the form of a ring compressed in place in a recess 8 in the casing *c* by a ring 7^a and the screw cap *v*, the ring 7^a being formed with a hole 9 20 that is constantly in communication with the air inlet port *n*.

Within the mixing chamber *a*, opposite the liquid fuel inlet port *d*, is a liquid fuel distributing device for causing the liquid fuel to assume a subdivided or film form. In the example shown in Fig. 1, the distributing device comprises a number of wires 10 arranged at an angle to the vertical, as shown in Fig. 3. The wires are 25 arranged in staggered relationship in sets, one below the other, so that liquid fuel admitted through the inlet port *d* will fall upon and cover them with a film of liquid which will first move along them in the direction of the arrow *y*, when the sleeve is 30 in the position shown in Fig. 3, and afterwards in the opposite direction when the oscillating body is moved in the direction of the arrow *z* to cause them to become inclined in the opposite direction as shown in Fig. 4.

The arrangement is such that assuming the oscillating body *b* has been moved by the rotating cam 4 into the position shown in Fig. 3 liquid fuel will enter the mixing chamber *a* through the inlet ports *d* and *e* for a short time and fall upon and flow over the distributing device 10, the supply of compressed air to the mixing chamber through the inlet ports *m* and *n* being then 45 cut off. Upon the body *b* being turned into the position shown in Fig. 4, the supply of liquid fuel through the inlet port *d* will have been cut off and the air inlet port *m* 50 in the body *b* will have been brought opposite the compressed air inlet port *n* so that compressed air will enter the mixing chamber *a*, come into contact with the bottom thereof and be deflected upward through the group of wires 10 so as to come into effective contact with the films of liquid fuel thereon and atomize the liquid fuel, forming therewith an intimate mixture of liquid fuel and air that will be discharged through 55 the outlet and delivery nozzles *u* and *u'* into

the furnace with which the apparatus is combined and wherein it will be ignited and burnt, forming an elongated flame.

Satisfactory results have been obtained with a mixing chamber *a* having a diameter of about one and a quarter inches, a movable liquid fuel inlet port *d* of about one eighth of an inch in diameter, moving past a stationary port *e* of about one quarter of an inch in diameter and a movable compressed air inlet port *n* and passage *t* each of about three sixteenths of an inch in diameter, the diameter of the outlet passage *u*² in the nozzle *u* being about five sixteenths of an inch, and that of the outlet end of the delivery nozzle *u'* about one and a quarter inches, the air pressure being about thirty pounds to the square inch. The liquid fuel may simply fall from the supply pipe *h* through the ports *e* and *d* with practically no more pressure than is necessary to cause it to flow.

In the modified arrangements shown in Fig. 5, liquid fuel is admitted to the mixing chamber *a* within a stationary body *c* through an inlet port *d*¹ of slot shape formed in an oscillating disc valve 11 provided with a spindle 12 and held tightly by a spring 13 against a stationary seat 14 formed with a port 15 in communication with the liquid fuel supply pipe *h*. The valve is suitably oscillated by a lever arm 16 on its spindle 12, as by cam or lever mechanism of any convenient construction, adapted to admit of the extent of oscillation of the valve being adjusted to suit requirement. The valve 11 is 90 located within a recess 17 that is formed in the base of a screw plug 18 and is in constant communication with the mixing chamber *a* through a hole 19 in the body *b*. Compressed air is admitted to the passage *t* in the body *b* by a similar oscillating disc valve 20 formed with a spindle 21 and slot shaped inlet port *m*¹ and held by a spring 22 against a fixed seat 23 having a port 24 therein in communication with the compressed air supply pipe *r*, the valve being suitably oscillated through a lever arm 25, as by cam or lever mechanism similar to that for oscillating the valve 11. In this example, the liquid fuel distributing device in the mixing chamber *a* is constituted by a coiled metal strip 10^a, conveniently of cork screw shape, arranged with its upper end directly below the liquid fuel inlet *d*¹.

In the modified arrangement shown in Figs. 6 and 7, a number of oscillating mixing chambers *a* with liquid fuel and compressed air inlet ports and controlling means of the kind hereinbefore described with reference to and shown in Figs. 1 to 4, are grouped around a common centre within a casing 26 and each having an outlet nozzle *u*¹. In this case, the several bodies *b* may be arranged to be oscillated in the proper order by a rotary cam 4 adapted to act upon the lever arms 1 125

fixed to the spindles *w* of the respective bodies *b*, the arrangement being such that an intimate mixture of liquid fuel and air will be produced in the several mixing chambers in consecutive order so that the stream of combustible mixture produced in each mixing chamber will be discharged through its nozzle *u*¹ before or at the termination of the discharge of mixture from a preceding mixing chamber and enable a continuous flame to be produced in a combustion chamber. Or, as hereinbefore described, the several mixing chambers may deliver streams of mixed liquid fuel and air into a single delivery nozzle common to them.

A drip pipe 27 may be provided at the front end of the nozzle *u*¹ (Fig. 1), or of each delivery nozzle, or of the delivery nozzle common to a number of mixing chambers, for the purpose of leading away, for reuse, any liquid fuel that may fail to become atomized by the air and be caught by the surface of the delivery nozzle, or each such nozzle, and down which it will drain. The front end of the delivery nozzle or each nozzle may advantageously be cut away to the curved shape shown and the drip pipe 27 be connected to a dished plate 28 secured to the bottom of the nozzle with its upper surface below the lower inner surface of the nozzle, as shown.

What I claim is:—

1. A method of producing an intimate mixture of liquid fuel and air in the correct relative proportions necessary to effect complete combustion of the liquid fuel, in a steam boiler or other furnace or apparatus, said method consisting in causing the liquid fuel and air successively to enter a mixing chamber at different parts thereof and in the said required relative proportions, the air being caused to impinge at an angle against the side of the chamber and be deflected therefrom at an angle thereto and come into contact with and atomize the liquid fuel, and delivering the resulting intimate mixture of liquid fuel and air from the mixing chamber to the combustion chamber of the furnace or apparatus where it is to be burnt and its heat utilized, substantially as described.

2. For producing a mixture of liquid fuel and air, apparatus comprising a mixing chamber having separate liquid fuel and air inlets and a contracted forward outlet, the air inlet being inclined to the longitudinal axis of said chamber, means for supplying liquid fuel and compressed air to said inlets and mechanically operated means adapted to open and control communication between the mixing chamber and liquid fuel and compressed air supply means in an intermittent manner, substantially as described for the purpose set for.

3. For producing a mixture of liquid fuel

and air in the correct relative proportions necessary to effect complete combustion of the liquid fuel, apparatus comprising an elongated mixing chamber closed at one end and having a mixture outlet at its opposite end and intermediate and separate inlets for liquid fuel and air, the air inlet being arranged between the liquid fuel inlet and the closed end of the chamber and inclined to the longitudinal axis of such chamber, means for supplying liquid fuel and compressed air to said mixing chamber, and means adapted directly and intermittently to control said liquid fuel inlet and air inlet and acting to admit air to the chamber after liquid fuel has been admitted thereto, substantially as described for the purpose set forth.

4. For producing a mixture of liquid fuel and air in the correct relative proportions necessary to effect complete combustion of the liquid fuel, apparatus comprising an elongated mixing chamber closed at one end and having a mixture outlet at its opposite end and intermediate and separate inlets for liquid fuel and air, the air inlet being arranged between the liquid fuel inlet and the closed end of the chamber and inclined to the longitudinal axis of said chamber, means for supplying liquid fuel and compressed air to said mixing chamber, liquid fuel distributing means arranged within said chamber adjacent to the liquid fuel inlet and over which admitted liquid fuel can spread, and means adapted directly and intermittently to control said liquid fuel inlet and air inlet and acting to admit air to the chamber after liquid fuel has been admitted thereto, substantially as described for the purposes set forth.

5. For producing a mixture of liquid fuel and air, apparatus comprising a stationary casing having liquid fuel and compressed air inlet ports, a hollow cylindrical body mounted to oscillate in said casing and having liquid fuel and compressed air inlets, the interior of said body forming a mixing chamber having a contracted outlet at its forward end, and means for oscillating said body, said body acting as a combined liquid fuel and compressed air admission and cut off valve to admit air and liquid fuel successively to said mixing chamber.

6. Apparatus according to claim 2, wherein in the communication between the interior of the mixing chamber and the liquid fuel and compressed air supply means is directly controlled by mechanically operated means arranged between the interior of said chamber and the fuel and air supply means and acting to admit liquid fuel and air successively to said chamber, substantially as described.

7. Apparatus according to claim 2, wherein in the mixing chamber is arranged horizon-

tally and has its liquid fuel inlet at its upper part and there is arranged below such inlet, means over which liquid fuel admitted to the chamber can fall and become distributed over the same, substantially as described for the purpose set forth.

8. Apparatus according to claim 2, where-
in the mixing chamber is made of elongated
oval form in longitudinal section and the
compressed air inlet passage is arranged to
deliver compressed air into it in an inclined
direction so that it will impinge upon the
surface thereof, substantially as described
for the purpose set forth.

15 9. For producing a mixture of liquid fuel
and air, apparatus comprising a plurality of
mixing chambers each having liquid fuel
and air inlets arranged one in front of the
other and a contracted outlet at its forward
end, means for supplying liquid fuel and
20 compressed air to said inlets, and mechani-
cally operated means for admitting liquid
fuel and compressed air successively to each
mixing chamber in turn so that a mixture of
25 liquid fuel and air will be produced in and
discharged from the successive mixing cham-
bers in consecutive order.

10. Apparatus according to claim 2, hav-
ing a forwardly extending tubular mixture
30 delivery nozzle extending from the con-
tracted forward end of the mixing cham-
ber, substantially as described for the pur-
pose set forth.

11. Apparatus according to claim 2, hav-
ing a forwardly extending mixture delivery
35 nozzle extending from the mixing chamber
and a drip pipe connected to the forward
end of said nozzle, substantially as described.

12. Apparatus for producing a mixture of
40 liquid fuel and air comprising a horizontal
mixing chamber of elongated oval shape in
longitudinal section and having a contracted
mixture outlet at its forward end and sepa-
rated liquid fuel and compressed air inlets
45 at its upper side, the air inlet being ar-
ranged behind the liquid fuel inlet and in-
clined to the lower side of the chamber,

means adapted to supply liquid fuel and
compressed air directly to the liquid fuel and
air inlets in definitely regulated propor-
50 tions for the purpose set forth, means acting
to open and close communication between
the means used for supplying liquid fuel
and air and said liquid fuel and air inlets
55 successively and a burner nozzle extending
from the outlet of said chamber and adapted
to direct flame resulting from the burning
of the mixture of liquid fuel and air pro-
duced in said chamber.

13. Apparatus for producing a mixture of
liquid fuel and air, comprising a stationary
casing having a liquid fuel and compressed
air inlets at its upper side, a hollow body
60 mounted to oscillate in said casing and hav-
ing liquid fuel and compressed air inlets at
its upper side adapted to register with the
corresponding inlets in said casing but at
different times, the interior of said body to-
65 gether with the forward portion of said
casing being adapted to form a mixing
chamber of elongated oval shape in longi-
tudinal section and provided with a con-
tracted outlet at its forward end, a burner
70 nozzle carried by said casing and in com-
munication with the forward end of said
chamber, liquid fuel and compressed air
75 supply pipes connected respectively to the
liquid fuel and compressed air inlets in said
casing, said air inlet being in communication
with an inlet passage inclined to the axis of
80 said chamber, and means for oscillating said
body in said casing to open and close said
inlets in alternate order, substantially as de-
scribed.

14. Apparatus according to claim 13 85
wherein liquid fuel distributing means are
arranged within the mixing chamber below
the liquid fuel inlet thereto and in the path
of air deflected from the side of said cham-
ber, for the purpose set forth.

Signed at London, England, this twenty-
third day of June 1922.

GUISEPPE GIDINO.
